[57] CLAIM

The ornamental design for a belt buckle, as shown and described.

DESCRIPTION

FIG. 1 is a perspective view of a belt buckle showing my new design;

FIG. 2 is another perspective view taken from an end opposite to FIG. 1 thereof;

FIG. 3 is a top plan view thereof;

FIG. 4 is a front view in elevation thereof;

FIG. 5 is a bottom plan view thereof;

FIG. 6 is an end view thereof;

FIG. 7 is a rear view in elevation thereof;

FIG. 8 is an end view taken from the end opposite to that shown in FIG. 6;

FIG. 9 is a perspective view of the belt buckle shown in FIG. 1 with the face removed from the center of the buckle;

FIG. 10 is another perspective view taken from the end opposite to that of FIG. 9 thereof;

FIG. 11 is a top plan view of FIG. 9;

FIG. 12 is a front view in elevation of FIG. 9;

FIG. 13 is a bottom end view of FIG. 9;

FIG. 14 is an end view of FIG. 9;

FIG. 15 is a rear view in elevation of FIG. 9; and

FIG. 16 is an end view taken from the end opposite to that of FIG. 14 thereof.
